UNITED STATES PATENT OFFICE.

CHARLES G. MERCER, OF EUFAULA, ALABAMA.

COTTON-CHOPPER.

SPECIFICATION forming part of Letters Patent No. 764,366, dated July 5, 1904.

Application filed February 24, 1904. Serial No. 195,082. (No model.)

To all whom it may concern:

Be it known that I, CHARLES G. MERCER, a citizen of the United States, residing at Eu-
5 faula, in the county of Barbour and State of Alabama, have invented new and useful Im-
provements in Cotton-Choppers, of which the following is a specification.

This invention relates to cotton-choppers of the class provided with oscillatory knives or 10 choppers.

The invention aims to provide a cotton-chopper with new and novel means, hereinafter more specifically referred to, which will admit of the chopper mechanism being raised 15 and lowered at the will of the driver without requiring the dismounting or the stopping of the machine, with means for throwing the mechanism into and out of operation, with means to prevent the breaking off and to permit 20 of the passage of the chopper or knife when meeting an obstruction, and with means for elevating the chopper mechanism by the foot of the driver, said means operable independently of the elevating and lowering 25 means hereinbefore referred to.

A further object of the invention is to devise a novel formation of framework, mounting, and connections for the operating parts, whereby the machine in its general construction 30 occupies a minimum amount of space and enables the least amount of material to enter into its formation consistent with strength and durability essential to the effectiveness and long life of the machine as compared with 35 others for a similar purpose and general construction.

The invention further aims to construct a cotton-chopper which shall be extremely simple in its construction, strong, durable, efficient in its use, and comparatively inexpensive to set up.

With the foregoing and other objects in view the invention consists of the novel combination and arrangement of parts hereinafter more specifically described, illustrated in the accompanying drawings, and particularly pointed out in the claims hereunto appended.

In describing the invention in detail reference is had to the accompanying drawings, 45 forming a part of this specification, wherein

like characters of reference denote corresponding parts throughout the several views, and in which—

Figure 1 is a side elevation of the machine; Fig. 2, a top plan view; Fig. 3, a front elevation; Fig. 4, a detail of the chopper or knife and its connections. Fig. 5 is a detail of a modified form of the chopper or knife, and Fig. 6 is an enlarged detail view of the bifurcated end of the pitman-rod.

The machine comprises a main rock-frame, a secondary rock-frame, an oscillatory chopper mechanism, operating means for the chopper mechanism, a hand-operated elevating and lowering means for the chopper mechanism and secondary rock-frame, and a foot-operated elevating mechanism for the chopper mechanism and secondary rock-frame.

Referring to the drawings by reference characters, 1 denotes the axle, upon which are mounted the wheels 2. These latter are each provided with a suitable pawl-and-ratchet mechanism of known construction to permit of a back movement thereof in relation to the axle, so that the machine can turn in any direction.

The reference character 4 denotes the shafts of the machine, and 5 a swingletree. The shafts and swingletree are secured to the front of the main rock-frame by any suitable holdfast devices.

The main rock-frame of the machine consists of an elongated strip of suitable material, preferably metal, bent to form the sides 6 and 7 and a front 8. The rear end of the sides 6 7 is loosely mounted upon the axle 1 to permit of rocking the frame, and the forward portion of the side 7 is bent outwardly in a curvilinear manner, as at 9, and said curvilinear portion terminates in one end of the front 8. The forward portion of the side 6 is also bent outwardly, as at 9', and terminates in the opposite end of the front 8. By constructing the sides 6 7 of the main rock-frame in a manner as set forth sufficient space is formed in the front portion of the main rock-frame to permit of the operation and arrangement of the chopper mechanism, to be hereinafter referred to. The shape of the main rock-frame, as shown, is substantially yoke-

shaped with the sides thereof at their forward portion bent outwardly for the purpose just set forth. Although the side 7 is shown as being constructed with a curvilinear portion 5 at its forward end, yet it is evident the contour of the portion 9 may be of any suitable shape.

The auxiliary rock-frame, which is arranged with the main rock-frame, consists of a yoke-shaped member 10, of any suitable material, having one of its sides of a greater length than the other, as indicated by the reference character 11, and said side of greater length at its rear is bent inwardly at right angles, as 10 at 12, and provided with a pair of notches to form seats 13 and 14 in its top edge. The auxiliary rock-frame at its rear is also loosely mounted upon the axle 1. Arranged within the yoke 10, as well as being secured thereto, 15 is a bracing as well as supporting bar 15, and to the said bar 15 is secured in any suitable manner a pair of hanger-arms 16. The hanger-arms 16 are also secured to the yoke-shaped member 10 in any suitable manner and are 20 arranged at one side of the auxiliary rock-frame. The hanger-arms 16 are of such length as to project forwardly of the auxiliary frame and terminate at a point removed from the front 8 of the main rock-frame.

25 The operating means for the chopper mechanism comprises a gear 17, mounted upon the axle 1, and a clutch mechanism 18 thereof, mounted upon the axle 1, having the shifting lever 19 thereof secured to the bar 15. The handle end of the lever 19 is adapted to engage in the seats 13 14 for connecting and disconnecting the gear 17 to and from the axle 1. The operating means for the chopper mechanism further comprises a pinion 20, 30 meshing with the gear 17, and said pinion 20 is carried on the rear end of the operating-shaft 21, which finds a bearing in the bar 15 and in the front of the secondary rock-frame. Suitable retaining-collars for the shaft 21 are 35 provided, as indicated by the reference character 22. On the forward end of the shaft 21 and in front of the secondary rock-frame is fixed a revolvable weighted disk 23, carrying on its front, near its edge, a wrist-pin 24, to 40 which is adapted to be adjustably connected, as at 25, one end of a pitman 26. The other end of said pitman 26 is bifurcated, as at 27, for the purpose hereinafter set forth.

The oscillatory chopper mechanism 45 comprises a pair of slotted members 28, suspended from the hangers 16 and which form guides for directing the travel of the chopper or knife to be presently referred to. The slots in the members 28 are arranged parallel to each 50 other and have a portion of their length—that is to say, the central portion thereof—extend in a transverse direction with respect to the machine. The remaining or end portions of each slot extend upwardly and outwardly and at an inclination, but in a direc-

tion opposite to each other. The function of the inclined portions in the slots of the members 28 is to guide the chopper or knife, to be hereinafter referred to, in such a manner that the beginning of its stroke, whether in one direction or the other, will be downwardly and inwardly at an inclination, thus facilitating the operation of the chopper or knife. Secured to the bifurcated end of the pitman 26 is a pin 29 and upon which is loosely mounted the upper end of the shank 30, which carries the chopper or knife 31, formed of an elongated flat piece of suitable material, preferably polygonal in contour, so as to have pointed ends and provided with a continuous 70 cutting edge, with the elongated portions thereof extending in the direction of travel of the machine. The pin 29 projects from each side of the bifurcated end of the pitman 26 and carries a guide-roller 32, operating in the slots 75 of the members 28, and the upper end of the shank 30 is formed with a lateral protuberance 33, which extends within the bifurcated end of the pitman 26 and is adapted to have its upper edge contact with the free end of a leaf-spring 34 and its lower edge contact with the free end of a leaf-spring 35. The spring 34 is secured at one end upon the upper edge of the pitman 26, and the spring 35 is secured at one 80 end to the lower edge of the pitman 26. By such an arrangement a yielding make-and-break connection is formed between the shank 30 of the chopper or knife and the pitman 26. This yielding make-and-break connection is provided for the purpose of preventing the 85 breaking off of the shank or the chopper or knife when an obstruction is met, for the reason that the yielding connection will permit of the moving of the shank of the chopper or knife out of the path of the obstruction. The 90 make-and-break connection is such that the shank of the cutter or knife can pivot in either direction and will cause the automatic return of the chopper or knife to its normal, or rather operative, position after it has been shifted.

The hand-operated elevating and lowering means for the oscillatory chopper mechanism and the auxiliary frame consists of a stud 36, secured to the upper face of one of the hangers 16, and pivoted to said stud 36 is the lower 105 end of a vertically-extending link 37, having the upper portion thereof formed with an elongated slot 38, in which slides a connecting-pin 39 for a bifurcated projection 40, carried on the lower end of a hand-operated lever 41, which is pivotally mounted upon a supporting-bar 42, secured to the main rock-frame. The supporting-bar 42 also carries a rack 43, which is adapted to be engaged by a lever-and-pawl connection 44, carried by the lever 41, 110 for locking the lever 41 after the oscillatory chopper mechanism has been adjusted, thereby retaining said chopper mechanism in its adjusted position.

The foot-operated elevating means for the 115

oscillatory chopper mechanism consists of a flexible connection 45, attached at its lower end to the stud 36 and at its upper end to the forward end of a foot-operated lever 46, which is pivoted upon the bar 42, as at 47. It is evident, owing to the pin-and-slot connection between the hand-operated lever 41, that when the driver operates the foot-lever 46 the chopper mechanism can be elevated independent of the primary elevating and lowering means; but when the foot-lever is released the chopper mechanism will be returned by gravity to the position to which it had been adjusted through the medium of the hand-operated mechanism, or, in other words, temporarily through the medium of the foot-operated elevating means the chopper mechanism can be elevated from its adjusted position; but when the foot-operated means is released the chopper mechanism returns to the position to which it had been adjusted by the hand-operated mechanism. Although the foot-operated mechanism operates independently of the hand-operated mechanism, yet these two mechanisms are used in conjunction with each other.

The reference character 48 denotes a seat-post supported upon the bar 42 and carrying a seat 49.

The operation of the chopper mechanism is as follows: Assuming that the gear 17 has been clutched to the axle 1 in the travel of the machine, motion will be imparted to the gear 17, which in turn will operate the pinion 20, rotating the shaft 21 and disk 23, imparting a reciprocatory movement to the pitman 26, the latter imparting an oscillatory movement to the shank 30 and chopper or knife 31. The latter has its chopping stroke directed downwardly and inwardly at an inclination and then upwardly and outwardly at an inclination, owing to the slotted guide members 28. If it be desired to increase or decrease the depth of the stroke of the chopper or knife 31, the hand-operated lever is moved forwardly or rearwardly, as the case may be, which in turn will elevate or lower the secondary rock-frame carrying the chopper mechanism and the operating mechanism therefor therewith. If it be desired to elevate the chopper mechanism after it has been set by the hand-operated lever, it can be accomplished by pressure upon the foot-lever, this lever being operated independently of the hand-operated elevating and lowering mechanism.

In Fig. 5 of the drawings is shown a modified form of chopper or knife and which is indicated by the reference character 31^a. The construction of the knife or chopper 31^a is the same as that of the chopper or knife designated by the reference character 31, with the exception that the forward end of the chopper or knife 31^a is slightly curved, as at 31^b, as it has been found that in large machines the curving of the forward end of the

chopper or knife facilitates the operation of 65 the same.

It is thought the many advantages of my improved cotton-chopper can be readily understood from the foregoing description, taken in connection with the accompanying drawings, and it will furthermore be evident that changes, variations, and modifications can be resorted to without departing from the spirit of my invention or sacrificing any of its advantages, and I therefore do not wish to restrict myself to the details of construction hereinbefore described and as set forth in the accompanying drawings, but reserve the right to make such changes, variations, and modifications as come properly within the scope 80 of the protection prayed.

Having thus fully described my invention, what I claim as new, and desire to secure by Letters Patent, is—

1. In a machine of the character described, 85 an oscillatory chopper pivoting in opposite directions, operating means therefor, and a yielding connection between said operating means and said cutter, said connection adapted to automatically return said chopper to its 90 operative position after it has been shifted on its pivot.

2. In a machine of the character described, 95 an oscillatory chopper pivoting in opposite directions and having a continuous cutting edge with elongated portions extending in the direction of the travel of the machine, operating means for said chopper, and a yielding connection between said operating means and the chopper, said connection adapted to automatically return the chopper to its operative position after it has been shifted on its pivot.

3. In a machine of the character described, 105 an oscillatory chopper pivoting in opposite directions, guides for said chopper, said guides provided with slots having portions extending at an inclination in opposite directions and said slots adapted to direct the travel of 110 said chopper, operating means for said chopper, and a yielding connection between said operating means and the chopper, said connection adapted to automatically return said 110 chopper to its operative position after it has been shifted on its pivot.

4. In a machine of the character described, 115 an oscillatory chopper pivoting in opposite directions, a guide for said chopper, said guide provided with a slot having portions extending at an inclination in opposite directions and said slot adapted to direct the travel of 120 said chopper, operating means for said chopper, and a yielding connection between said operating means and the chopper, said connection adapted to automatically return said 120 chopper to its operative position after it has been shifted on its pivot.

5. In a machine of the character described, 125 an oscillatory chopper pivoting in opposite

directions, means for automatically returning the chopper to its normal position after it has been shifted on its pivot, and operating means for the chopper.

5 6. In a machine of the character described, an oscillatory chopper pivoting in opposite directions, and means for automatically returning the chopper to its operative position after it has been shifted on its pivot.

10 7. In a machine of the character described, a chopper, a shank for supporting it, said shank provided with a lateral projection, a pitman having a bifurcated end adapted to receive the upper end of the shank and said lateral projection, means for pivotally connecting the shank to the bifurcated end of the pitman, said shank pivoting in opposite directions on said pivot, a pair of springs carried by the pitman and adapted to retain said chopper in 15 its operative position and to return said chopper to its operative position when the same has been shifted on its pivot, and means connected with the pitman for imparting an oscillatory movement to said chopper.

20 8. In a machine of the character described, a chopper, a shank for supporting it, said shank provided with a lateral projection, a pitman having a bifurcated end adapted to receive the upper end of the shank and said lateral 25 projection, means for pivotally connecting the shank to the bifurcated end of the pitman, said shank pivoting in opposite directions on said pivot, a pair of springs carried by the pitman and adapted to retain said chopper in 30 its operative position and to return said chopper to its operative position when the same has been shifted on its pivot, means connected with the pitman for imparting an oscillatory movement to said chopper, and means for guiding said chopper downwardly and inwardly 35 and upwardly and outwardly at an inclination during the oscillations thereof.

40 9. In a machine of the character described, a chopper, a shank for suspending it, said shank having a lateral projection, operating means for the chopper, means for pivotally connecting the shank to said operating means, said connecting means permitting of the shank pivoting in opposite directions, and means 45 engaging with said projection for returning the chopper to its normal position after it has been shifted upon its pivot.

45 10. In a machine of the character described, a chopper pivoting in opposite directions, and 50 means for automatically returning the chopper to its normal position after it has been shifted upon its pivot.

55 11. In a machine of the character described, a main rock-frame, supporting means therefor, an auxiliary rock-frame arranged within the main frame and connected to said supporting means, an oscillatory chopper pivoting in opposite directions supported between the front of the secondary frame and the front 60 of said main frame, operating means for the 65

chopper interposed between the main frame and the secondary frame, said operating means supported by said secondary frame, a hand-operated elevating and lowering means for said secondary frame supported by the 70 main frame, and a foot-operated means for elevating said secondary frame supported by the main frame and operating independently of the hand-operated means.

75 12. In a machine of the character described, a rocking frame, hangers carried thereby, an oscillatory chopper suspended by said hangers, operating means for said chopper supported by said frame, a yielding connecting means between said operating means and said 80 chopper, said means adapted to return the chopper to its normal position after it has been shifted on its pivot, means for elevating and lowering said frame, and means for elevating said frame independent of the means 85 for elevating and lowering it.

90 13. A machine of the character described comprising a chopper mechanism, a revolute weighted disk, operating means for said disk, a chopper-mechanism-oscillating pitman adjustably connected at one end to the disk and having its other end bifurcated, and a make-and-break connection between the bifurcated end of the pitman and the chopper mechanism.

95 14. A machine of the character described, a chopper, slotted guide members therefor, a pitman for oscillating the chopper, a pin for pivotally connecting the chopper to one end of the pitman, said pin projecting from each side of the pitman, rollers carried by the projecting ends of the pin and operating in the slots of the guides, and means connected to the other end of the pitman for operating it.

100 15. A machine of the character described comprising a chopper, a pitman for operating the chopper, a pivotal connection between the chopper and the pitman, said connection forming a guide for the chopper, means for supporting the pivotal connection, said means adapted to cause the travel of the chopper downwardly and inwardly and upwardly and outwardly at an inclination, and means for operating the pitman.

11 16. A machine of the character described comprising a chopper, slotted guide members therefor, a pitman for oscillating the chopper, a pin for pivotally connecting the chopper to one end of the pitman, said pin projecting from each side of the pitman, rollers carried by the projecting ends of the pin and operating in the slots of the guides, means connected to the other end of the pitman for operating it, and means carried by the pitman for returning the chopper after it has been shifted on its pivot to its operative position.

12 17. A machine of the character described comprising a chopper, a pitman for operating the chopper, a pivotal connection between the 13

chopper and the pitman, said connection forming a guide for the chopper, means for supporting the pivotal connection, said means adapted to cause the travel of the chopper 5 downwardly and inwardly and upwardly and outwardly at an inclination, means for operating the pitman, and means carried by the pitman for returning the chopper to its operative position after said chopper has been 10 shifted on its pivot.

18. A cotton-chopper comprising a chopper mechanism, a hand-operated mechanism for vertically adjusting said chopper and retaining it in its adjusted position, and a foot-operated mechanism operating independently of said hand-operated mechanism and adapted to elevate said chopper from its adjusted position, said chopper adapted to return to the 15 position to which it had been adjusted by the hand-operated mechanism when the foot-operated mechanism is released.

19. In a cotton-chopper comprising an oscillatory chopper mechanism, a hand-operated mechanism for vertically adjusting said chopper and retaining it in its adjusted position, and a foot-operated mechanism operating independently of said hand-operated mechanism and adapted to elevate said chopper from its adjusted position, said chopper adapted to 25 return to the position to which it had been adjusted by the hand-operated mechanism when the foot-operated mechanism is released.

20. In a machine of the character described, a chopper, a shank for supporting it, a pitman for imparting oscillations to the chopper, means for pivotally connecting the shank to one end of the pitman, said shank pivoting in opposite directions on said pivot, means carried by the pitman and adapted to engage with 35 said shank for retaining the chopper in its operative position and for returning said chopper to its operative position when the same has been shifted upon its pivot, means connected with the pitman for operating it, and 40 means engaging with the pivot between the shank and pitman for guiding the stroke of the chopper downwardly and inwardly and upwardly and outwardly at an inclination.

21. In a machine of the character described, 45 the combination with a revoluble axle, a main rock-frame having an enlarged forward end and loosely mounted at its rear end upon said axle, a secondary rock-frame arranged within the main rock-frame and loosely mounted at 50 its rear end upon said axle, a chopper mechanism supported by the secondary frame, operating mechanism for the chopper mechanism driven from the axle of the machine and supported by the said secondary frame, means 55 carried by the axle and adapted to engage in the secondary frame for connecting and disconnecting said operating mechanism to and from the axle, and means carried by the main rock-frame for vertically adjusting said secondary frame and chopper mechanism and for 60

retaining said secondary frame and chopper mechanism in the position adjusted to.

22. In a cotton-chopper, a chopper or knife having a continuous cutting edge, said knife having its forward end slightly curved. 70

23. In a cotton-chopper, a chopper or knife having a continuous cutting edge, said knife having its forward end curved.

24. In a cotton-chopper, a chopper or knife having a continuous cutting edge with elongated portions extending in the direction of the travel of the machine, said knife having its forward end curved. 75

25. In a cotton-chopper, a chopper or knife having a continuous cutting edge with elongated portions extending in the direction of the travel of the machine, said knife having its forward end slightly curved. 80

26. In a cotton-chopper, a polygonal-shaped chopper or knife having a continuous cutting edge with the elongated portions thereof extending in the direction of the travel of the machine, said knife having its forward end curved. 85

27. In a cotton-chopper, a polygonal-shaped chopper or knife having a continuous cutting edge with the elongated portions thereof extending in the direction of the travel of the machine, said knife having its forward end slightly curved. 90

28. In a machine of the character described, a revoluble axle, a main rock-frame having its forward end enlarged and loosely mounted at its rear end upon said axle, a secondary rock-frame arranged within the main rock-frame and loosely mounted at its rear end upon said axle, said rock-frame having one of its sides provided with a rearward extension having its upper edge formed with a plurality of seats, a chopper mechanism supported by said secondary rock-frame, operating means for said mechanism driven from the axle of the machine and supported by said secondary frame, a clutch mechanism carried by the axle and adapted to engage in said seats for connecting and disconnecting said operating means to and from the axle of the machine, a hand-operated means carried by the main frame and connected with the secondary frame and adapted when operated to vertically adjust said chopper mechanism and retain it in its adjusted position, and a foot-operated means carried by the main frame and connected with the secondary frame and operating independently of said hand-operated means and adapted when operated to elevate the chopper mechanism from its adjusted position, said chopper mechanism adapted to return to the position to which it had been adjusted by the hand-operated mechanism when the foot-operated mechanism is released. 105

29. In a machine of the character described, a revoluble axle, a main rock-frame having its forward end enlarged and loosely mounted at its rear end upon said axle, a secondary rock- 110

115

120

125

130

- frame arranged within the main rock-frame and loosely mounted at its rear end upon said axle, said rock-frame having one of its sides provided with a rearward extension having its 5 upper edge formed with a plurality of seats, a chopper mechanism supported by said secondary rock-frame, operating means for said mechanism driven from the axle of the machine and supported by said secondary frame, 10 a clutch mechanism carried by the axle and adapted to engage in said seats for connecting and disconnecting said operating means to and from the axle of the machine, a hand-operated means adapted when operated to vertically 15 adjust said chopper mechanism and retain it in its adjusted position, and a foot-operated means operating independently of said hand-operated means and adapted when operated to elevate said chopper mechanism from 20 its adjusted position, said chopper mechanism adapted to return to the position to which it had been adjusted by the hand-operated mechanism when the foot-operated mechanism is released.
- 25 30. In a machine of the character described, a revoluble axle, a main rock-frame having its forward end enlarged and loosely mounted at its rear end upon said axle, a secondary rock-frame arranged within the main rock-frame and 30 loosely mounted at its rear end upon said axle, said rock-frame having one of its sides provided with a rearward extension having its upper edge formed with a plurality of seats, depending guide members carried by said secondary frame, a chopper mechanism operating in and supported by said guide members, operating means for said mechanism driven from the axle of the machine and supported by said secondary frame, a clutch mechanism carried by the axle and adapted to engage in said seats for connecting and disconnecting said operating means to and from the axle of the machine, a hand-operated means 35 adapted when operated to vertically adjust said chopper mechanism and retain it in its adjusted position, and a foot-operated means operating independently of said hand-operated means and adapted when operated to elevate said chopper mechanism from its adjusted position, said chopper mechanism adapted to return to the position to which it had been adjusted by the hand-operated mechanism when the foot-operated mechanism is released.
- 40 45. In a machine of the character described, a revoluble axle, a main rock-frame having its forward end enlarged and loosely mounted at its rear end upon said axle, a secondary rock-frame arranged within the main rock-frame and connected with the main frame and carried by the main frame and connected with the secondary frame and adapted when operated to vertically adjust said chopper mechanism and retain it in its adjusted position, and a foot-
- operated means carried by the main frame and connected with the secondary frame and operating independently of said hand-operated means and adapted when operated to elevate the chopper mechanism from its adjusted position, said chopper mechanism adapted to return to the position to which it had been adjusted by the hand-operated mechanism when the foot-operated mechanism is released.
31. In a machine of the character described, a revoluble axle, a main rock-frame having its forward end enlarged and loosely mounted at its rear end upon said axle, a secondary rock-frame arranged within the main rock-frame and loosely mounted at its rear end upon said axle, said rock-frame having one of its sides provided with a rearward extension having its upper edge formed with a plurality of seats, depending guide members carried by said secondary frame, a chopper mechanism operating in and supported by said guide members, operating means for said mechanism driven from the axle of the machine and supported by said secondary frame, a clutch mechanism carried by the axle and adapted to engage in said seats for connecting and disconnecting said operating means to and from the axle of the machine, a hand-operated means adapted when operated to vertically adjust said chopper mechanism and retain it in its adjusted position, and a foot-operated means operating independently of said hand-operated means and adapted when operated to elevate said chopper mechanism from its adjusted position, said chopper mechanism adapted to return to the position to which it had been adjusted by the hand-operated mechanism when the foot-operated mechanism is released.

In testimony whereof I have hereunto set my hand in presence of two subscribing witnesses.

CHARLES G. MERCER.
